UNITED STATES PATENT OFFICE.

LLOYD G. TAYLOR, OF BALTIMORE, MARYLAND.

DESIGN FOR A BOTTLE.

Application filed July 7, 1926. Serial No. 18,267. Term of patent 14 years.

To all whom it may concern:

Be it known that I, LLOYD G. TAYLOR, a subject of the Dominion of Canada, residing at 211 E. North Ave., in the city of Baltimore, State of Maryland, have invented a new, original, and ornamental Design for a Bottle, of which the following is a specification, reference being had to the accompanying drawing, forming part thereof.

Fig. 1 is a perspective view of a bottle, showing my new design. Fig. 2 is a view looking in the direction of the arrow 2 in Fig. 1.

I claim:

The ornamental design for a bottle as shown.

LLOYD G. TAYLOR.
